UNITED STATES PATENT OFFICE.

HARRY BRIDGMAN SMITH, OF BROOKLYN, NEW YORK.

METHOD OF MAKING COVERED PAPER BOXES.

1,402,260.

Specification of Letters Patent.

Patented Jan. 3, 1922.

Application filed March 31, 1920. Serial No. 370,180.

To all whom it may concern:

Be it known that I, HARRY BRIDGMAN SMITH, a citizen of the United States, and resident of Brooklyn, in the county of Kings 5 and State of New York, have invented certain new and useful Improvements in Methods of Making Covered Paper Boxes, of which the following is a specification.

My present invention which is a continuation in part of my co-pending application Serial No. 254,630, filed September 18, 1918, relates generally to the art of making covered paper boxes, such as are now commonly employed in packaging various articles or products of merchandise, as, candy, soap, articles of wearing apparel and other commodities.

One object of the invention is to provide an entirely new method of making covered paper or paper-board box shells of known types as well as certain distinctly new types.

A further object of the invention is to provide a method of making covered paper boxes from an assembly consisting of a shell blank having a body portion and side and end wings and a cover blank of greater dimensions than the shell blank wherein many of the difficulties heretofore encountered in 25 making covered paper boxes are entirely obviated, prominent among such difficulties being the natural curling tendency of the cover material when moist adhesive is applied thereto.

Another object of the invention is to provide for accurate registration of the box shell blank with its wrapper blank in order that the latter may be more neatly applied.

Other more or less important objects are contemplated and provided for, as will be made clear in the detailed description to follow.

According to the methods and machines now generally employed in the manufacture of covered paper boxes, the cut or "cornered" box shell blanks are first bent or folded into box form, the corners "stayed" with suitable corner-staying material, and the covering blank or wrapper which has adhesive applied to one face thereof is then applied to the outer walls of the box shell,

sometimes by hand and sometimes by machinery. In some instances it has been proposed to eliminate the corner-staying operation, but in all such cases, so far as I am aware, it has been the practice to first fold the box shell into box form and then apply a freshly gummed or glued covering blank or wrapper thereto.

Many attempts have been made to provide a continuous method and also to produce an entirely automatic machine for making covered paper boxes of the type referred to. In every instance, so far as I am aware, 65 the automatic machines heretofore proposed include in their organization a mechanism for gumming the thin wrapper blanks; instrumentalities for applying the gummed wrapper blanks to the box shells; and mechanism for transporting the gummed wrapper blanks from the gumming mechanism to the box covering instrumentalities. Some of the machines also include means for automatically feeding thereto the "stayed" box 70 shells to be covered.

Great difficulties have been encountered in the attempts heretofore made to successfully operate machines of these types, due among other things to the tendency of the 80 thin paper covering blanks to curl immediately fresh gum or glue is applied to a face thereof, resulting in much bad work and waste. Because of this curling of the blanks, the consequent waste, and other troubles, 85 including imperfect registration, these automatic machines have not been successful where attempts have been made to operate them commercially.

Many attempts have been made to prevent 90 or counteract this curling tendency of the blanks resulting from the application thereto of fluid gum or adhesive. In some cases the blanks have been steamed or otherwise moistened during or after the application 95 of the glue in order to kill the curling tendency. In others an attempt has been made to hold the glued wrapper blanks flat by mechanical means as they pass from the gumming mechanism to the wrapper applying mechanism. In others, attempts have been made to so organize the machines 100 that the gumming mechanism would be arranged close up to the wrapper applying

mechanism with the object of delivering the wrappers quickly and before they had an opportunity to curl. While some of these various attempts to obviate the blank curling tendency may have proved satisfactory as to this particular item, the means suggested besides being complicated brought about numerous new difficulties, and so far as I am aware, a satisfactory automatic machine has not yet been produced, and the old practice of employing separate hand operators to feed the blanks to the gumming machine and also to the operator of the cover-applying machine is still carried on, notwithstanding the slowness and increased expense of such procedure.

I have discovered after extensive and costly experiments, that the previously existing difficulties which have been encountered due to the curling tendency of the wrapper blanks when fresh adhesive is applied thereto, as well as the many other difficulties, including imperfect registration, are entirely obviated or overcome and the wrapper blanks more accurately, neatly, quickly and cheaply applied, by first applying the adhesive to the relatively stiff box shell blank (which will not curl appreciably when moistened with adhesive), and by then applying the ungummed wrapper blank to the gummed face of the box shell blank to provide a box forming "assembly" consisting of a box shell blank and an attached cover blank which may then be folded into box form. Such a procedure, I have discovered, not only overcomes the objections incident to the curling of the cover blanks as described as well as other objections, but very materially simplifies and cheapens other operations incident to the formation of the finished box.

So far as I am aware I am the first in the art of making covered boxes, to suggest and provide for the application of the cover or wrapper affixing adhesive to the relatively stiff box blank direct, instead of to the thin and flexible wrapper blank, for the purpose stated, and I therefore lay claim to this procedure broadly.

I have also discovered that the box forming and wrapper applying operations may be more rapidly, cheaply, accurately and expeditiously performed by first producing what I will term, an "embryo" box forming "assembly," consisting of a substantially flat box shell blank and an applied cover or wrapper blank with opposite marginal edges of the cover blank folded over opposite edges of the shell blank and adhesively affixed thereto. The assembly thus produced may then be folded into box form and maintained in its "set up" condition without requiring separate corner staying operations.

According to this part of my improved method I first apply adhesive material to the

flat or unfolded box shell blank direct, the adhesive being applied to said blank in spots or zones, as by stencilling, or over the entire face thereof, and in some instances in spots or zones applied to both faces, or 70 spots or zones on one face and throughout its entire area on the other face, the manner of applying the adhesive depending upon the type or style of box to be manufactured. This application of the adhesive to the relatively stiff box shell blank does not cause appreciable bending or curling thereof and all difficulties incident to such curling are entirely overcome. I then assemble the adhesively coated box shell blank and the 75 80 wrapper blank in superposed relation, while these elements are substantially flat, and I also inturn and affix marginal portions and the wrapper blank to certain of the adhesive zones or stencil lines of the shell 85 blank while these elements are substantially flat, thereby producing what I have termed an "embryo" box forming "assembly."

By the procedure described it will be seen that the operations of covering the box shell 90 blank, including a part of the marginal "turn-in" are actually completed before said blank is folded into the final box form.

I have demonstrated that I can produce, according to my improved method, and with 95 an apparatus designed to carry out said method, covered paper boxes of various kinds, including the so-called "tight wrapped" and "loose wrapped" boxes, as well as other kinds, more economically, in 100 greater quantities and of better and more uniform quality, than by any other method or apparatus heretofore employed or provided.

In order to enable others skilled in the art 105 to understand and practice my said invention, I will now proceed to describe a preferred embodiment thereof, but I wish it distinctly understood that this showing is merely illustrative or by way of example 110 and is not, therefore, to be considered in any way restrictive, except as I may be restricted by the terms of the appended claims, as it will be perfectly obvious to others reading this specification in connection with the 115 appended drawings, that changes, variations or additions may be made both to the method and to the apparatus without departing from the broad spirit of the invention.

In order that the full scope of the invention may be understood and appreciated I have elected to show in the accompanying drawings a preferred procedure employed in making several different types of covered boxes, including "tight" and "loose" wrapped, but, I do not wish to be understood as limiting myself to these specific types as obviously others may be made by the same procedure or slight variations 120 125 130

thereof without departing from the spirit of the invention, as will hereinafter more fully appear.

In the annexed drawings:

- 5 Figures 1 to 9 inclusive, represent in perspective the various steps employed in making one form of "loose wrapped" box according to my improved method.
- 10 Figures 10 to 18 inclusive, represent in perspective the various steps employed in making another form of "loose wrapped" box according to my improved method.
- 15 Figures 19 to 27 inclusive, represent in perspective the various steps employed in the manufacture of a "tight wrapped" box made in accordance with my improved method.
- 20 Figure 28, is a side elevation of the essential mechanisms embodied in one form of mechanical means for carrying out my improved method.
- 25 Figure 29, is a similar view of a portion of such mechanism, with certain of the parts in a different position from that illustrated in Figure 28.
- 30 Figure 30, is a view similar to Figure 29 showing the position of the glue applying stencil when taking glue from the glue applying roll.
- 35 Figure 31, is an elevation of a portion of the described mechanism showing the position of the parts during the marginal turning-in operation and the "assembly" folding-up operation.
- 40 Figure 32, is a cross sectional view on an enlarged scale of a part of the marginal edge turning-in mechanism.
- 45 Figure 33, is a vertical sectional view taken through the assembly folding mechanism, and also showing the means for peeling the gummed end wings of the shell blank from the corresponding wings of the cover or wrapper blank, and showing also the means for advancing the formed up and covered box shell.
- 50 Figure 34, is a plan view partly in section showing the means for folding up the end wings of the assembly.
- 55 Figure 35, is a top plan view of the mechanism for folding up the end wings and corner laps of the covered assembly.
- 60 Figure 36 is a vertical transverse section taken on the line of 36—36—Figure 28.
- 65 Three different types of boxes have been illustrated by way of examples. These are shown in completed form in Figures 9, 18 and 27. The two former are of the "loose wrap" variety, so-called because the cover blank is wrapped loosely about the exterior of the box shell; and the other is of the "tight wrap" variety, so-called because the wrapper is glued throughout its entire area to the exterior of the box shell.
- 70 All of the boxes shown are made from box shell blanks having corner laps which are folded inward toward each other at the ends of the finished box to strengthen the corners thereof, and which, together with other portions of the blank form multiply box wall ends. In some cases these corner laps are located interiorly of the box shell, as in the box illustrated in Figure 9, while in others the corner laps are located exteriorly of the box shell, as in the boxes illustrated in Figures 18 and 27. These differences in the location of the corner laps are illustrative of some of the variations of which my improved method is susceptible and the results obtained from such variations, namely, different types or styles of boxes. Of course the same method may be employed in making boxes wherein the shell blank is not provided with corner laps.
- 75 I will first describe the steps or operations performed in making each of the three types of boxes herein illustrated and will then describe one form of mechanism I have elected to show as a preferred embodiment of mechanical means for performing such steps or operations, it being understood that in each case the first operation is to form an embryo box forming "assembly" consisting of a substantially flat box shell blank, usually of relatively stiff card-board or box-board stock, creased or scored and slit 80 or cornered as usual, and an attached cover blank of relatively thin paper or other readily foldable material and which is sometimes plain and sometimes decorated by printing and embossing, either or both, said 85 cover blank being usually cornered.
- 90 In Figures 1 to 9 inclusive I have illustrated the various steps as successively performed in making one type of "loose wrapped" box according to my improved method. 95 This is a distinctly new type of box, one new feature residing in the fact that portions of the wrapper blank are infolded at the ends of the box and lie in between the plies of the multiply end walls formed by the corner laps and adjacent overlying end wings at the ends of the box, the said infolded portions covering the raw edges of the end wings as will more fully hereinafter appear.
- 100 In this type of box S designates the box shell blank, which is usually of stiff card-board or box-board material and W designates the wrapper or cover blank, which is usually of plain or ornamental finishing paper.
- 105 The shell blank S, in the instance illustrated, is cut and scored or creased to provide the usual folding lines, and consists of a body portion a, having integral side wings b, corner laps c and end wings d. The side 110 and end wings and corner laps, when folded at right angles to the body portion a, of the blank, form a box shell having multi-ply end walls, the corner laps in this particular style of box being located interiorly thereof.
- 115 120 125 130

Shell blanks of this type are now in common use, but the usual practice has been to apply the cover or wrapper blank thereto, after the shell blank has been completely set up 5 into box form and stayed at the corners although in some instances the cover has been applied to the folded box shell without first corner staying the latter. According to my improved method, I propose to apply the 10 wrapper blank to the shell blank while the latter is substantially flat, producing a flat covered "assembly" which is afterwards folded and "set up" into box form.

The wrapper blank *W* in the instance 15 shown consists of a sheet of relatively thin and readily foldable paper or other flexible material and is of general cruciform shape, and of greater dimensions than the shell blank *S*, leaving marginal portions that may 20 be folded about the marginal edges of the shell blank, as will presently appear.

In making the flat "assembly" consisting of the relatively stiff shell blank and the wrapper blank, according to my improved 25 method, I first apply zones or stripes of adhesive *e*, to one face of the shell blank around the marginal edges thereof, as shown in Figure 1. This blank in its flat form is then superposed in proper registration relation upon an ungummed wrapper or cover blank of the type referred to, as shown in Figure 2. The two blanks having been combined as shown in said figure, and while they are still in a flat condition, I turn 30 the free projecting marginal portions *f* of the wrapper or cover blank over the opposite edges of and cause such portions to become adhesively affixed to the gummed marginal portions *e*, on the exposed face of the shell blank, as more clearly shown in Figure 3, thus making an "assembly" consisting of 40 a shell blank and its applied wrapper or cover blank. It will be seen that the marginal portions *f*, of the cover blank are extended so that they project over and cover a portion of the edges of the corner laps *c*, and in the finished box these covered portions lie in between adjacent faces of the multi-ply end walls.

45 The "assembly" having been formed as described, I then fold up, (or down as the case may be) the two covered side wings *b*, as shown in Figure 5, forming the side walls of the box shell, these walls being then completely covered including the "turn in" as 50 clearly appears in the drawing. This folding operation is preferably performed about an inner support such as a form block or plunger. The corner laps *c*, at the opposite 55 ends of the side wings *b*, are then infolded toward each other, as shown in Figure 6, the four corner laps being preferably inturned simultaneously. During the corner lap infolding operation, the portions of the wrap- 60 per blank carried by the corner laps are also

inturned and the end wings *d*, simultaneously folded up against the infolded corner laps to produce the structure illustrated in Figure 7, it being understood that as the corner laps *c*, and the end wings *d*, are folded as described, the free portions of the wrapper blank at the corners of the box are infolded in the form of "gusset" folds, so as to cause the latter to lie in between adjacent faces of the multi-ply end wall plies formed 70 by the corner laps *c*, and the end wings *d*, the said infolded portions also covering the raw edges of the end wings of the shell blank, so that no such edges are exposed.

75 As will be seen by referring to Figures 1 80 to 5 inclusive, the end wings *d* of the shell blank are provided with adhesive all around the free marginal portions thereof. This is done for the purpose of securely attaching projecting side marginal portions *g* of the 85 end wings of the cover blank when these portions are infolded as described, and also to provide adhesive zones for maintaining the box shell in final set up form.

85 After the corner laps and end wings have 90 been infolded in the manner stated to produce the structure shown in Figure 7, the remaining upstanding marginal portions of the cover or wrapper blank at the opposite ends of the box are then inturned over the 95 upper edges of and adhesively affixed to the adhesive stripes or zones carried by the end wings and corner laps forming the end walls of the box shell to complete the covering and "setting up" operations.

100 A squeezing pressure is then applied to the inturned portions just described to cause them to become more firmly affixed so that the inturned marginal portions may serve in and of themselves to maintain the box in its 105 final "set up" condition as illustrated in Figure 9, it being understood that all the folding and "setting up" operations are carried on very quickly after the shell blank has been stencilled and before the glue has had 110 a chance to set or dry.

115 It will thus be seen from the foregoing procedure that my improved method of making covered paper boxes differs very materially from all previously known methods, in that I first provide a substantially flat "assembly" consisting of a shell blank and a superposed cover blank, by applying the required adhesive to a face of the relatively stiff shell blank and then combining 120 the shell blank with the unglued wrapper blank, thus obviating the difficulties and waste which occur from curling when liquid adhesive is applied to the thin wrapper or cover blank before its application to the 125 box shell as heretofore practiced.

130 My improved method also differs from known methods in that the marginal edges of the wrapper blank at the side siges of the shell blank are inturned over and affixed

to such edges of the shell blank while the latter is maintained substantially flat, or in other words, before the shell blank is folded into box form, and the marginal edges of the 5 end wings of the wrapper folded over and affixed to the interior of the box shell as a final step which completes the "setting up" operation and serves, along with the adhesively connected corners laps, to maintain 10 the folded shell into box form.

In Figures 10 to 18 inclusive I have shown the various successive steps in the manufacture of another form or type of "loose wrapped" box made according to my 15 improved method. In this particular type of box the corner laps are located exteriorly of the end wings of the shell blank, but they are covered by the applied wrapper or cover blank as will be seen.

20 In these figures, reference S' designates the shell blank of relatively stiff box-board stock and W' designates the wrapper or cover blank. The shell blank S' consists of a body portion a' having integral side 25 wings b' , each having corner laps c' at the ends thereof, and end wings d' . The cover or wrapper blank W' is of general cruciform shape and its side wings are provided with transverse slits g' spaced a short distance 30 from the ends thereof to provide lips or tongues h' for a purpose presently to appear.

35 In making this style of box I proceed in precisely the same manner as heretofore described with reference to the box illustrated in Figures 1 to 9 inclusive, by first stencilling the shell blank on one face around its marginal edges, then superposing the flat shell blank onto the flat cover or wrapper blank, then inturning the projecting marginal edges f' over the marginal edges of and adhesively affixing them to the stencilled edges of the shell blank, leaving the 40 lips or tongues h' projecting or lying in the plane of the "assembly" as shown in Figure 12.

The side wings b' of the "assembly" are 50 then folded up at right angles to the body portion thereof and the end wings d' are likewise folded up, these operations preferably taking place while the embryo box shell is interiorly supported as by a form blank. Where mechanical means are employed to fold the "assembly" into the form 55 of a box, the end wings are folded up by lifting devices having engagement therewith while the side wings are being folded and preferably during an advancing movement of the "assembly".

60 The function of the free laps h' is to cover the raw edges of the corner laps and the end wings adjacent the vertical box corners. These free laps are inturned over the marginal edges of the end wings of the 65 corner laps at the ends of the box at the

same time the free marginal edges of the end wings of the cover blank are inturned over such edges. It is customary in many types of loose wrapped boxes to fold the end wings of the cover blank in such a way 70 that the edges thereof will be arranged on converging lines as shown. By this arrangement the upper portion of each folded end wing is narrower than its base so that unless some provision is made for covering 75 the marginal edges of the shell blank at the ends of the box such edges would be exposed, which would be objectionable. By slitting the cover blank at the points g' to provide the free laps h' as described, provision is made for covering those portions 80 of the marginal edges of the formed box shell adjacent the corners, so that a completely finished box results.

85 In Figures 19 to 27, inclusive, I have illustrated the various steps performed in making what is known as a "tight wrapped" box according to my improved method. The term "tight wrapped" is employed because the wrapper blank is adhesively attached to 90 the exterior walls of the box shell throughout as distinguished from being loosely applied and unattached as in "loose wrapped" boxes.

95 In making these "tight wrapped" boxes according to my method I proceed in substantially the same manner and employ substantially the same folding operations as carried out in making "loose wrapped" boxes except as to the application of the adhesive 100 to the box shell and as to the folding of the corner laps which are shown as being arranged exteriorly of the end wings of the box shell instead of interiorly thereof as in some of the other types of boxes.

105 As shown in Figure 19, the box shell blank S'' consists of a body portion a'' having side wings b'' b'' each having corner laps c'' at their ends and end wings d'' . The wrapper blank W'' is of substantially the same shape 110 as the box shell blank S'' except that the side wings are wider than the corresponding wings of the shell blank and the end wings thereof are preferably of the same width as the corresponding wings of the shell blank but slightly longer so as to provide marginal portions that may be infolded about the marginal edges of the shell blank and adhesively affixed to the inner walls of the 115 finished box.

120 Adhesive is applied to one face of the box shell blank around the marginal edges thereof at e'' , as shown in Figure 19, and the other face thereof is coated throughout with adhesive, as shown in Figure 20. The two blanks are then arranged in superposed relation, the face of the shell blank that has been coated throughout being placed upon the upper face of the wrapper blank W'' to provide a "flat" assembly.

In superposing the adhesively coated face of the shell blank S'' upon the uncoated upper face of the wrapper or cover blank W'' , in the production of the assembly, provision is made for preventing adhesive attachment of intermediate portions of the end wings of the shell blank to corresponding intermediate portions of the end wings of the wrapper or cover blank, in order to permit subsequent separation of the end wings of the two blanks to provide what I have termed an "offset" method of gluing the end wings of the cover or wrapper blank. That is to say, opposite end portions of the end wings of the wrapper or cover blank are provided with adhesive which is received or taken from adhesively coated portions of the end wings of the shell blank during the assembly operation so that the adhesively coated portions of the wrapper blank may be adhesively attached to the uncoated portions of the corner laps of the side wings, when such corner laps are infolded at right angles to their wings, in the formation of the box. This method of "offset" gluing I believe to be distinctly new and as it forms an important part of my invention I have claimed the same broadly in my co-pending application Serial No. 431,910, filed December 20, 1920.

In practicing this part of my invention, by means of mechanical instrumentalities, I propose to interpose relatively thin plates P between the end wings of the cover and wrapper blank, as these two are being superposed one upon the other, as shown in Figures 21 and 22, these plates being of less width than the width of the end wings of the shell and cover or wrapper blanks, so that, when the two blanks are brought into superposed relation and pressed together to cause them to adhere one to the other, opposite end portions only of the adhesively coated end wings will contact with the corresponding portions of the end wings of the wrapper or cover blank, the plates P holding the intermediate portions of the two blanks separated. The separating plates P are each provided with a longitudinal slot or opening to permit suitable grippers as hereinafter described, to pass therethrough and grasp or grip the edges of the end wings of the shell blank and peel or separate them from adhesive attachment with the end wings of the cover or wrapper blank, the latter wings being held down during the peeling or separating operation by means of grippers 38, Figs. 23 and 33. This peeling operation, of course, takes place while the glue or adhesive is still in a moist condition and separation of the blanks may therefore be readily effected. As a result of the separation the opposite marginal edges of the end wings of the cover or wrapper blank are provided with spots or

zones x of glue as illustrated in Figure 24, so that such portions of the blank may be subsequently attached to inturned un-coated portions of the corner laps as above described.

After the two blanks have been adhesively connected in the manner described, the projecting marginal edges of the side wings of the wrapper blank are then infolded over and adhesively affixed to the gummed marginal edges of the side wings b'' of the shell blank as shown in Figure 22, thus completing the flat assembly. The end wings d'' are peeled or separated from the corresponding wings of the cover or wrapper blank as previously described after the marginal edge turn in operation and during the assembly folding operation.

The side and end wings of the shell blank are then folded up at right angles to the body portion, as shown in Figure 23, and are held in their folded condition in any suitable way, the end wings of the cover or wrapper blank, which have been provided with "offset" gluing, remaining flat, as shown in said figure. The projecting corner laps at the ends of the side wings are then infolded and held into adhesive attachment with the adhesively coated faces of the end wings of the shell blank to provide the structure shown in Figure 24, and while so held the end wings of the cover or wrapper blank are folded up and adhesively attached to the infolded corner laps and the exposed portion of the end wings of the box shell to provide the structure shown in Figure 25, the "offset" glued portions now coming into play. Then the projecting marginal portions of the end wings of the cover or wrapper blank are then turned over the marginal edges of the end walls of the box structure as shown in Figure 26, after which these marginal edges are turned down and adhesively affixed to the adhesively coated edges of the end walls to complete the setting up and covering operation and thus provide the covered box as illustrated in Figure 27.

I prefer in all cases to perform the folding operations of the assembly about a form-block or plunger which is approximately the size, as to area, of the body portion of the shell blank, the form-block or plunger constituting an inner support for the box shell during the formation thereof, the employment of the box form insuring squareness of the finished box and permitting pressure to be applied exteriorly of the shell while on the form.

I have illustrated and described only one type of so-called "tight wrapped" box of which there are many, but it will be perfectly obvious from the disclosure that all types of both "tight and loose wrapped" boxes may be made according to my method without departing from the spirit of the invention, the

essential feature in each case being the making of a substantially flat assembly from previously prepared shell and cover blanks, the assembly being then folded into box 5 form, the operations of folding the assembly also serving to complete the application of the wrapper blank.

Having described the steps or operations performed in making several different kinds 10 of boxes of the "tight" and "loose" wrapped type according to my invention, I will now proceed to described one type of mechanism for performing my method by mechanical instrumentalities. These instrumentalities 15 in the instance shown are arranged to produce a succession of assemblies and deliver them successively to a mechanism for folding them into box form. I do not wish to be understood, however, as limiting myself to 20 the precise form of mechanism illustrated, as obviously other forms of mechanism may be employed without departing from the spirit of the invention. Nor do I wish to be understood as limiting myself to the employment 25 in a single machine of all the different mechanisms about to be described, as it will be perfectly obvious from the showing that some of the mechanisms may be omitted entirely leaving others to perform useful functions 30 in association with each other or in association with other mechanisms.

It will be apparent to those skilled in the art to which my invention appertains, that the mechanism herein disclosed for making 35 flat assemblies from flat box shell and cover blanks, may be employed for this purpose, whether the adhesive is applied to the shell blank or to the cover blank, and this is especially true in the matter of preparing as 40 semblies for the manufacture of "loose wrapped" boxes where adhesive is applied only to the marginal edges of one of the blanks. So far as I am aware I am the first in the paper box making art to provide me 45 chanical means for preparing and assembling two flat blanks of the kind referred to in the manufacture of box forming assemblies, and wherein the blanks are maintained flat or substantially so during the assembly 50 forming operations.

In making covered boxes of the "loose wrapped" type, according to my improved method, it will be seen that no glue is applied directly to the thin cover or wrapper 55 blanks, such as would have a tendency to cause the blanks to curl, this curling tendency therefore, with the objections and difficulties resulting therefrom is entirely avoided by my method. In making tight wrapped 60 boxes according to my improved method, only relatively small spots or zones of adhesive are applied to the cover or wrapper blank, but these are applied in such a way and at such a time that no curling of the 65 blank is possible, since the end wings of the

cover blank to which the spots or zones of glue have been applied are held from any curling tendency by the adhesive attachment of the wings of the cover blank to the wings of the shell blank until just prior to the 70 time when the cover blank wings are to be finally and permanently affixed.

I do not lay claim in the present application to the box constructions or the assembly or assemblies per se, as these are claimed in 75 my co-pending applications, Serial No. 235,515, filed May 20, 1918, Serial No. 235,516, filed May 20, 1918 and Serial No. 272,907, filed January 24, 1919.

One of the important advantages resulting from my improved method of making covered paper boxes in the manner described resides in the fact that I am able to employ relatively light stock for the cover blanks, since I have entirely eliminated the 80 troubles heretofore encountered by reason of the curling tendency of the cover blanks in those methods where the adhesive is applied directly thereto. Where liquid adhesive is applied directly to the cover blanks, 85 according to the methods heretofore employed, it has been necessary to employ relatively heavy stock in order to lessen the curling tendency as much as possible. As paper stock is usually sold by weight, I am 90 able, by reason of my new method, to utilize the lighter grades of covering papers and a material saving in the cost of the finished product is thereby effected.

In Figures 28 to 36 inclusive I have shown 100 one form of mechanism for carrying out in a simple manner and very expeditiously the required "assembly" forming and box folding operations, only so much of the mechanism being shown as to give a clear understanding of the construction and operation 105 thereof and more particularly the construction and operation of the mechanism essential to the manufacture of the flat "assemblies" from which the boxes are to be 110 formed. This "assembly" forming mechanism is a machine complete in itself, but I have shown it in association with box forming instrumentalities so that the disclosure of the essential elements of a machine for 115 forming completely covered boxes will be complete. The box folding mechanism may, of course, be varied to suit the requirements, the mechanism shown being merely by way of example.

According to the construction and plan of operation of the "assembly" forming and folding mechanism illustrated, I provide a plurality of stations arranged in series, each having devices thereat, or associated therewith, to perform a certain definite step or operation in the several steps or operations required to produce and deliver the finished box forming "assemblies" and for folding them into finished boxes. The construction 120

and arrangement of the various parts of the machine are such that the devices at several of the stations are each operating upon an assembly-element or elements at the same time, so as to increase the capacity of the machine which may be said to be of the "stage" type. The machine thus automatically produces a succession of finished "assemblies" which are automatically delivered 10 to the box folding and "setting up" instrumentalities where they are formed into finished boxes or covers as the case may be.

In short, the mechanism is designed to produce a succession of embryo box forming 15 "assemblies," each comprising a substantially flat box shell blank and an attached wrapper blank, and said mechanism includes a plurality of stations, each having devices thereat or associated therewith for performing a 20 succession of "assembly" forming operations, and means co-operating with said stations for transferring the assembly-elements from one station to another in succession.

In the machine illustrated, I have shown 25 three stations which co-operate in the production of the "assembly," and have also shown in association therewith, a box forming station. For convenience of description I have lettered and will hereafter refer to 30 these stations as follows:

A—shell blank supply station,
B—stencil and shell blank gumming station,
C—wrapper blank supply and "assembly" 35 station,
D—box forming station.

A shell-blank stencilling and transporting device, and an assembly transferring device or carrier, are co-operatively associated 40 with the "assembly" forming stations referred to. The shell-blank stencilling and transporting device operates to carry the shell blanks successively from the shell blank supply station to the "assembly" forming 45 station, and the "assembly" carrier or transferring device operates to transfer the finished "assembly" and carry it into or partially through the box folding mechanism, it being understood always that the "assembly" forming elements, i. e., the shell blank and the cover or wrapper blank, as well as the "assembly" itself, are always maintained in a flat or substantially flat condition until the "assembly" is delivered into 50 the box folding mechanism.

The shell-blank transporting and the "assembly" transferring devices operate in conjunction with the "assembly" forming stations to apply adhesive to the relatively stiff 60 shell blank either on one or both faces, depending upon the style of box being made, then transfer the adhesively coated shell blank and deliver it flatwise onto its wrapper blank, and then transfer the finished "assembly" to the "assembly" folding mecha-

nism to form it into a "set up" and completely covered box.

The shell blank transporting device A' and the "assembly" transferring or carrying device B' are both mounted upon a carriage 70 1, of any suitable construction, which carriage is preferably provided with anti-friction rollers 2, which travel or ride upon a trackway or trackways 3, the latter being supported in any suitable manner as by rods 75 4. A vertically reciprocating motion is imparted to the trackway 3, by any suitable means (not shown), so that as the trackway moves up and down, the carriage with its transporting and transferring devices A' 80 and B' move with it. In addition to its vertically reciprocating movements, the carriage is mounted to travel back and forth horizontally upon the trackway or trackways 3, these horizontal movements being 85 effected by means of a rock lever 5, having a link connection 6 with the carriage, as more clearly shown in Figure 28. The horizontal movements of the carriage bring the shell-blank transporting device A' and the 90 "assembly" transferring device B' into co-operative relation with the several stations A, B and C. Of course, the movements of the carriage are timed to co-ordinate with the movements of other parts of the machine 95 as will hereinafter more fully appear.

The shell-blank transporting device A' consists of a head carrying rubber or other glue applying stencil strips 7, adapted to apply the lines or zones of glue e, to the upper face of a shell blank, and there is also provided a combined shell-blank support and stripper plate 8, which is adapted to be housed within the boundary of the stencil strips 7, and which has a movement relative 100 thereto, effected by any suitable means, such as rack and pinion mechanism 9, the said plate 8 being mounted upon a rod 10. During the application of glue to the stencil strips, as will be hereinafter described, the 105 combined support and stripper plate is retracted in an elevated position above the plane of the under face of the stencil strips, but it is also adapted to assume a position in substantially the plane of the stencil 110 strips in order to constitute a support for a shell blank when the latter is receiving glue over its entire under face, as in the manufacture of "tight wrapped" boxes. It is also adapted to assume a position below 115 the plane of the stencil strips, as during the operation of producing the box forming "assembly" at the "assembly" forming station, as will presently appear. The "assembly" carrier or transferring device which is 120 also carried by the carriage and moves therewith, consists of a pair of grippers of any suitable construction and which may be operated in any suitable way to cause them to grip the two opposite end wings of 125 130

the "assembly" after it has been formed to transfer or carry the same into association with the box folding instrumentalities.

The shell blank supply station A in the instance shown is constructed to hold a stack of shell blanks 6, in the "flat," the stack being supported upon a follower 13, which is normally urged upward by any suitable means, so that as the blanks are taken from the stack, the uppermost blank thereof will always be at a proper level to take the glue from the stencils 7, of the stenciling device forming a part of the transporting device A', as will presently appear. A rack and pinion mechanism such as 14, is employed to quickly lower the follower 13 into a position to receive a new supply of blanks and to afterward elevate the follower to the normal position.

20 The wrapper blank supply station C also has a follower block 15 which is normally urged upward in the manner described with reference to follower 13, and a rack and pinion mechanism 16, is also employed to raise and lower the follower to replenish the supply of wrapper blanks.

As will be seen by referring to Figure 28 the follower 15 constituting the support for the wrapper blanks is normally located on a plane below the normal plane of the support 13 for the shell blanks and selecting mechanism is provided for successively taking wrapper or cover blanks from the top of the pack and deliver them singly into position where the shell blanks may be assembled therewith in the formation of the box forming "assembly", the two blanks or "assembly" forming elements being always maintained in the "flat". This cover blank selecting mechanism in the instance shown, consists of a suction head 17, journalled upon a shaft 18, carried by vertically sliding blocks 19, which latter move in guideways 20, properly spaced at opposite sides of the wrapper blank support. The blocks 17 are jointed to the lower ends of vertically reciprocating rods 21, each pivoted at its upper end to an oscillating lever 22, the said levers and rods constituting the means for reciprocating the blocks 17, in their guideways 20. The shaft 18 on which the suction head 17 is mounted, carries a pinion or pinions 23, which, during the upward movement of the suction head 55 engage with fixed racks 24, arranged in the path of movement of the pinions, so that as the suction head is moved upward with its selected wrapper blank it will be given a half turn so as to bring its suction face with its wrapper blank carried thereby into a position facing upward, the said suction head with its blank being adapted to assume an elevated position to have superposed thereon the selected shell blank carried by the transporting device A', which at this

moment in the operation of the machine occupies a position directly over the suction head.

When the parts are in this position which is the initial assembling position for the shell and cover or wrapper blanks, the assembly transferring device including the two grippers 25 or 25', is in the dotted line position, Figure 28, having carried a completed assembly into position to be forced through or into the assembly folding instrumentalities, as will presently appear.

The stencil gumming station B is situated between the blank supply stations A and C, and in the instance shown, the gumming mechanism consists of a tank or glue pot 26, pivotally mounted at 27, so as to be oscillated about its pivot. One means for effecting oscillation thereof is to provide the tank with a bifurcated bracket 28, between the legs of which is a rotary cam 29. The glue pot or tank 26, in the instance shown is divided by a central longitudinally extending partition dividing the tank into two compartments in each of which is mounted a glue applying roll indicated as 30 and 31. These rolls are mounted to rotate in opposite directions, the roll 30 rotating in an anti-clockwise direction and the roll 31 operating in a clockwise direction. The rolls are arranged to co-operate with the shell blank stenciling and transporting device A', and the glue pot oscillating or tilting cam 29 is so timed as to cause the roll 30 to contact with and apply glue to the stencils 7 during the movement thereof from the assembly forming station back to the shell-blank supply station, the position of the parts during this operation being illustrated in Figure 30. The glue applying roll 31, is arranged to make contact with the under face of a shell blank carried by the transporting device A' during the movement of said device from the shell blank station to the assembly forming station. If there is glue in the compartment of the glue pot or tank in which the roll 31 rotates, then the under face of the shell blank carried by the transporting device A' will receive a surface coating of glue over the entire area thereof, as shown in Figure 20, and as required in the manufacture of what are known as "tight wrapped" boxes. In the manufacture of "loose wrapped" boxes, no glue is required on the under face of the shell blank, therefore, when manufacturing boxes of this style there is no glue in the compartment of the glue pot or tank in which the roll 31 rotates. The roll 31, however, is caused to exert a rolling pressure upon the blank carried by the stencils 7, of the transporting device A' moving thereover to exert pressure thereagainst and insure a uniform application of the glue by the stencils as the blank is transported from its pack to the assembly

forming station. The position of the parts during this operation is shown in Figure 29, said figure also showing the assembly transferring device as carrying a completed assembly over toward the assembly forming mechanism.

It will be seen from the foregoing that the glue applying device operates, according to one plan of operation, to apply glue to the face of the stencils as they are moved thereover in one direction, and to exert pressure upon the transported shell blank during the movement thereof in the opposite direction; and this device also operates when doing another class of work, namely "tight wrapped" work, to apply glue to the stencils during the movement thereover in one direction and to apply glue over the entire area of the under surface of the shell-blank during movement thereover in the opposite direction.

Where glue is placed in both compartments of the tank or pot, I prefer to employ a relatively strong and quick setting glue in the compartment in which the roll 30 rotates, and a weaker and more slowly setting glue in the compartment in which the roll 31 rotates. The reason for this is that parts of the stencilled portions of the blank are employed in the setting up or corner staying operation thus requiring a strong glue; whereas a weaker glue is all that is necessary to adhesively connect the two blanks of the "assembly," and besides, peeling of the end wings in the "offset" gluing operation as heretofore described, is more readily accomplished where a weak and slow setting glue is employed.

The station C, has located thereat the marginal edge turn-in mechanism, i. e., devices for turning the marginal edges *f*, of the wrapper blank *W*, over the opposite edges of and affixing them by pressure to the adhesively coated edges of the side wings *b*, of the box shell blanks as heretofore described with respect to Figures 3, 12 and 22. These marginal edge turning-in devices, as more clearly shown in Figures 31 and 32, consist of a pair of fixed bars 32, with each of which is associated a pivoted or hinged presser bar 33, the latter being arranged with relation to the bars 32 so that as the presser bars are rocked on their hinges or pivots, the free marginal edges of the wrapper blank of an assembly situated therebetween will be turned over and adhesively affixed by pressure to the glue coated marginal edges of the side wings of the shell blank, as previously described. The pivoted or hinged bars 33 may be operated by any suitable means and by preference they are so mounted as to be adjusted laterally to operate upon blanks of different sizes. In the instance shown, each bar 33 is mounted upon a rock shaft 34, journalled at its op-

posite ends in suitable bearings not shown. The said shaft 34 carries a crank 34', to which is connected a link 34'', and by which the shaft 34 may be rocked to cause the bars 33 with their presser blocks to inturn and affix the marginal edges of the cover or wrapper blank to the stencilled edges of the shell blank. During this marginal edge turning operation, the assembly is supported from beneath by means of the suction head 17 and from above by means of the ejector plate 8, forming a part of the shell blank transporting device A', as shown in Figure 31. By reason of the fact that the "assembly" is firmly held in a flatwise condition during the marginal edge turning-in operation, a more uniform and accurate turn-in is secured.

By referring to Figure 29 it will be seen that the space between the bars 32 of the marginal turn-in mechanism is less than the maximum width or length of the wrapper or cover blank, but since these blanks are flexible, the said bars 32 offer no obstruction to the free passage of the wrapper blank therebetween, as the ends of the blank simply flex or bend as they are being carried upward between the bars by means of the suction head 17. This head with the blank held thereto by suction is moved up by means of the link 21 and lever 22 until it meets a stencilled blank carried by the shell blank transporting device A', whereupon the two blanks are brought together in assembled relation. Then the trackway 3 with its carriage 1, moves downward as a unit for a short distance, and at the same time the ejector plate 8 is caused to move, by means of the rack and pinion mechanism 9, out of its housed relation to the stencils 7, the said plate 8 and suction head 17 being then brought to a position to hold the clamped "assembly" in the plane of the upper face of the bars 32 of the marginal edge turn-in mechanism, this downward movement of the assembly causing the free marginal portions *f*, of the cover blank to engage the edges of the marginal edge turn-in bars 33, so as to fold the free marginal edges *f*, of the cover blank up at right angles to the body of the "assembly," as more clearly shown in Figure 32, after which the turn-in bars 33 are rocked to properly bend and affix such marginal edge portions of the wrapper blank to the stencilled portions of the shell blank, completing the "assembly" which is then grasped by grippers 25 or 25' of the assembly transferring device at the proper moment to carry the same over to the box forming instrumentalities, while the blank transporting device A' is bringing a fresh shell blank into position to be applied to a fresh wrapper blank. It should be understood that while the assembly transferring device and the shell blank transport-

ing and stencilling device are operating to deliver a completed "assembly" and bring over a fresh shell blank, the suction head has in the meantime descended to select a 5 fresh wrapper blank and carry it to a position for assembly with the shell blank.

Assembly folding or box forming mechanism.

10 While I prefer to combine the assembly forming mechanism with a box forming mechanism of some kind, such as the instrumentalities located at station D, now to be described, I do not wish to be limited to 15 such a combination as it will be apparent that the assembly forming mechanism is a machine complete in itself. Nor do I wish to be understood as limiting myself to an arrangement wherein the shell blanks and 20 wrapper blanks are supplied from packs or stacks of such blanks as in stations A and C, as they may be otherwise applied without departing from the broad spirit of the invention. Furthermore, I do not wish to be 25 understood as limiting myself to the specific means illustrated for applying adhesive to the blanks or for delivering the finished assemblies, as means for this purpose may be varied within wide limits without departing 30 from the spirit of the invention. In short, I believe myself to be a pioneer in the broad features of the herein described method, and an apparatus for carrying the same into effect and am, therefore, entitled to protection 35 as such.

The box forming mechanism and its location with respect to the other parts of the machine is indicated generally by the letter D in Figure 28. The details of one form of 40 such mechanism are more clearly illustrated in Figures 6, 14, 23, 33, 34 and 35.

According to the plan of operation of this mechanism, the box forming assembly is carried to a position directly above a pair of 45 rubber faced wing bending rolls 25, the assembly being carried to this position by the transferring device B' and held by means of the grippers 25 or the sucker holders 25', as shown in Figure 4. A form block or 50 plunger 36 carried by a rod 37 is caused to engage the body portion a, of the assembly after the latter has been properly positioned as described, and carries the assembly through the box forming instrumentalities, 55 first holding up the side wings of the assembly, then infolding the corner laps thereof at the ends of the box, and then either simultaneously with said corner lap folding operation, or subsequently thereto, de- 60 pending upon the style of box being made, the end wings of the assembly are folded to position, and as a final operation or operations the marginal edges of the wrapper blank are turned over the upper edges of 65 and adhesively affixed to the inner walls of

the box ends. The thus folded assembly now in its finished box form is then moved through a confining channel where it may be shaped by suitable "shaping" means acting on the exterior walls thereof, and may then be moved in association with means for applying glue to the inner marginal edges thereof for the purpose of affixing lace edging strips to the box, (if the boxes being made are to receive such strips), otherwise 70 the said gluing means will not be employed.

In moving downward into the assembly folding instrumentalities the plunger 36 first carries the assembly between the opposed rubber faced rolls 25, these serving to fold up 80 the side wings of the assembly about the opposite sides of the form block 36, so that the assembly will assume either one of the positions shown in Figures 5, 13, or 23, depending upon the style of box being made. 85 In each case it will be seen that the corner laps of the assembly, together with adjacent portions of the cover or wrapper blank, will project beyond the ends of the form block. The carriage 1, with its assembly transferring device also moves down for a short distance, as the plunger moves down, the grippers of the transferring device retaining their hold on the end wings of the shell blank, as shown in Figure 33, as where tight 90 wrapped boxes are made. The carriage with its grippers 25 then returns to normal position, the grippers lifting the end wings of the shell blank and peeling them from adhesive connection with the associated end 95 wings of the wrapper blank. During this moment the wings of the wrapper blank are held down by suitable grippers 38, Figure 33, thus providing for offset gluing of the said end wings. When the end wings of 100 the shell blank have been lifted to upstanding position, holding devices such as rods 39 are caused to engage and hold the said end wings against the end walls of the plunger until the corner laps of the assembly 105 have been turned in and affixed thereto.

The corner laps are infolded by means of two pairs of opposed corner lap "turn-in" wings, each consisting of a metal blade 49, Figures 6 and 23, each pair of said blades being adjustably mounted upon a bar 41. The bars are moved in and out by any suitable means, so as to cause the wings 40 to approach each other in the act of turning in the corner laps at the ends of the box. In addition to the corner lap folders described, I also provide at each end of the box and in substantially the plane of the lap folding wings 40, appropriate lifting means operating simultaneously with the wings 40 115 for lifting up or folding the end wing portions of the assembly at the ends of the box, as illustrated in Figures 6 and 14, gusset or bellows folds being formed in some instances at the free portions of the wrapper 120 125 130

- blank adjacent the corners of the box, as shown in said figures. These gusset or bellows folds form a neat appearance in the wrapper at the ends of the box, as more 5 clearly illustrated in Figures 9 and 16. In making boxes of the type or style illustrated in Figure 9, the free portions of the wrapper blank at the ends of the box adjacent the corners thereof are folded so as to lie in between the corner laps and the end wings of the box shell blank, portions of the wrapper blank covering the opposite raw edges of the end wings of the shell blank.
- An important feature of the mechanism 10 and its operations is that the corner lap turn-in wings 40 are caused to retain their hold on the corner laps while the end wings are being folded up to position, thus greatly facilitating the folding and setting up operation, the said wings 40 being retracted just as the end wings assume their final position.
- The mechanism referred to for folding up the end portions of the assembly and forming the gusset or bellows folds as described, is more clearly shown in Figures 6, 34 and 35, and consists of a pair of laterally movable folding plates 42 and an intermediate folding plate 43, said plates being mounted 15 upon a squared shaft 44, the plate 43 being fixed to the shaft 44 and the plates 42 being slidably mounted thereon, and each normally urged outward by means of a coiled spring 45. One end of each spring is attached to a block 46, carrying the central folder plate 43 and its other end is attached to a block 47 carrying its associated folder plate 42, each block 47 being mounted to move longitudinally upon the shaft 44. In 20 the folding operation the folder plates 42 are caused to move inward toward each other as said plates are moved upward and they gradually resume their normal position as they are moved outward and downward. To accomplish this operation I provide each end of the squared shaft 44 with an eccentric 48, each mounted in a bearing 49, carried by bracket arm 50, as more 25 clearly shown in Figure 6. Each bearing 49 is provided on its inner face with a cam projection 51, arranged adjacent its associated eccentric and each folder plate block 47 is provided with an outwardly projecting lug 52, which engages or rides over the 30 face of its associated cam 51, so that as the eccentrics are rotated in their bearings 49, the folder plates will move upward in the arc of a circle and inward toward each other to effect the folding operations, as more 35 clearly shown in Figure 6. The means for rotating the eccentrics and the squared shaft 44 consists of a rotating shaft 53, Figures 34 and 35, having a crank arm 54 at one end thereof, which arm acts upon a block 46, to 40 which the central folder wing 43 is attached.
- The end of the crank arm 54 in its travel through the arc of a circle, contacts with the block 46, causing the shaft 44 to rotate, thus elevating the folding plates 42 and 43. The shaft 53 is rotated by any suitable means not 45 shown.
- The end wings of the assembly having been folded up in the manner described and the gusset or bellows folds formed, (if the box is of the type having bellows folds), the 50 box then assumes a position illustrated in Figures 7, 15 or 25, depending upon the style of box being made. The box is then covered over its entire exterior and is complete except for the operation of folding 55 over and affixing the marginal edges of the wrapper blank to the inner walls at the ends of the box to complete the "setting up" operation.
- The plunger 36 now carries the box further 60 down and into a well, having walls 56, Figure 28, and deposits it upon a suitable supporting plate 57, as more clearly shown in Figure 33. Leading outward from the well 56, is a channel formed as a continuation of the bottom plate 57, the opposite marginal edges of the channel being provided with fixed folding wings 58, which operate during movement of the box to fold the projecting portions of the wrapper blank 65 over the free edges of the box shell end walls, bringing such edges to a position shown in Figures 8, 16 and 26. The box is caused to travel through the said channel by means of a plurality of pairs of fingers 59, which are 70 arranged in spaced relation to engage a plurality of boxes to move them through the channel simultaneously by step movements, the fingers being mounted upon oscillating and longitudinally reciprocating shafts 60. 75 The shafts are oscillated in one direction to move the fingers outwardly away from the boxes and in the opposite direction to move them inwardly and into engagement with the boxes, as they are successively delivered 80 by the plunger 36 at the bottom of the well 56 adjacent the channel. Upon moving through the folders 58 the boxes are delivered beneath a second plunger 61, mounted upon a vertically reciprocating rod 62 and 85 immediately the box is positioned beneath the plunger 61, the latter enters the same carrying with it the turned over marginal edges of the wrapper. Arranged adjacent the walls of the box at this position of the channel, is a pair of presser blocks 63, as more 90 clearly shown in Figures 17 and 36, said blocks being operable to impart a squeezing pressure to those portions of the end walls of the box that have had their marginal 95 edges turned down by the plunger 61, this squeezing pressure operating against the plunger to firmly affix such marginal edges to the inner walls of the box. The plunger is then moved upward out of the box 100

and the whole series of boxes is advanced in the manner heretofore described, bringing the foremost box beneath a shaper consisting of a plurality of fingers 64, mounted 5 upon a vertically reciprocating rod 65, said fingers being adapted during the downward movement thereof to engage the vertical side walls of the box and bend them inward to take out any outward flare or bulge that 10 may be present in said walls, it being common knowledge in the art that there is a tendency of the walls of boxes of this kind to bulge or flare outwardly when a cover or wrapper has been applied thereto, especially 15 where moist glue is employed. If the finished boxes are to have lace papers or edging strips applied to the interior thereof, I may further provide means for applying zones or stripes of glue to the inner faces 20 of the side walls of the boxes. This may be accomplished as the boxes move along the channel by providing glue applying stencils which have a movement into and out of the box and toward and from the inner marginal edges of the side walls thereof. Suitable 25 glue applying rolls 66 are of course arranged to apply glue to the stencils as they are moved out of the box. This mechanism is more clearly shown in Figure 28. The operation of the machine briefly stated is as follows.

Assuming the parts to be in the position illustrated in Figure 28 and the glue applying stencils 7 having been coated with glue, 30 the trackway 3 is now lowered until the stencils 7 come into contact with the uppermost blank S of the pack of shell blanks resting on the support 13, thus stenciling said blank around its marginal edges as at e. 35 At the same time the "assembly" transferring device B' is lowered until its grippers 25 or 25' engage and grasp the end wings d of the shell blank forming a part of the previously made "assembly". The trackway 40 is now raised, elevating the carriage 1 and with it the transporting device A' and transferring device B', the former having a shell blank S adhering to its glue coated stencils and the device B' having a finished assembly 45 in its grasp. During this movement of the parts the suction head 17 has selected a wrapper or cover blank W from the pack of blanks on the support 15 and carried it up to a position to receive the oncoming shell 50 blank. The carriage is now moved to the right by the lever arm 5 and during this movement the shell blank is caused to ride into contact with the roller 31, as shown in Figure 29. If "loose wrapped" boxes are 55 being made, in which case there will be no glue on the roller, then the roller acts simply as a presser roll to more firmly press the blank S against its stencils in order to insure a more uniform application of glue 60 thereto. If "tight wrapped" boxes are be- 65 ing made, then the roll 31 will act to apply a coating of glue over the entire area of the underside of the shell blank S carried by the stencils 7 and also act as a presser roll as described. The carriage has a fixed limit 70 of travel and when it comes to rest in its outward movement the stencils with their shell blank S will assume a position directly over the wrapper blank W carried by the suction head 17, and the previously formed 75 assembly which is now in the grasp of the grippers 25 or 25' will have been carried over the entrance of the assembly folding instrumentalities D and properly positioned relative thereto and to the plunger 36. The carriage now begins to move down until the flat shell blank S carried by the stencils 7 is superposed upon and in exact registration contact with the flat wrapper blank W, supported upon the suction head 17. At the 80 same time the transferring device B' is carrying the finished assembly into the folding instrumentalities, the grippers 25 or 25' retaining their hold upon the end wings d of the shell blank. The carriage then begins to 85 move up, but the plate 8 associated with the stencils 7 remains in clamping contact with the two superposed blanks resting upon the suction head, the latter now assuming the position illustrated in Figure 31, wherein 90 it will be seen that the assembled blanks are ready for the marginal edge turn-in operation which now takes place. This operation is effected by the turn-in bars 33, as previously described. The carriage continues its upward movement, during which the grippers 25 or 25' of the transferring device B' raise the end wings d of the shell blank 95 so that the rods 29 Figure 23 may move into engagement with and hold the wings against 100 the end walls of the form block 36, holding them in this position until the corner-laps of the assembly have been infolded and affixed thereto as previously explained. The carriage now moves back to its initial position, during which movement the stencils 7 come into contact with the glue applying roll 30 to receive a fresh supply of glue for the next blank, as shown in Figure 30. While 105 the carriage is thus returning the suction head 17 is moving down for a new wrapper blank and the plunger 36 is carrying the finished assembly through the box folding instrumentalities.

The operations described are repeated continuously, a freshly gummed shell blank and a finished assembly being delivered at each outward movement of the carriage and the stencils receiving a fresh coating of glue at each return movement.

An important feature of the machine and its operation resides in the manner in which the shell and wrapper blanks are selected, transported and assembled, the one being deposited "flatwise" directly upon the other.

This insures perfect registration which is essential to a uniform product. So far as I am aware I am the first in the box making art to select, transport and assemble blanks 5 in the manner described and I lay claim thereto broadly.

In making loose wrapped boxes of the type illustrated in Figures 1 to 9 inclusive, wherein portions *g* of the wrapper blank 10 *W* are inturned about the opposite raw edges of the end wings *d* of the shell blank, the inwardly and upwardly moving folder plates 42 shown in Figures 6 and 35 have inturned lips 42' spaced from the plates 15 proper, these lips being adapted to engage the side marginal portions *g* of the wrapper blank and fold them about the opposite edges of said end wings *d* to cover the raw edges thereof. In making boxes of the type 20 illustrated in Figures 19 to 27 inclusive, the plates 42 are not provided with the lips as described,—a flat plate being all that is required.

I do not claim in the present application 25 the mechanism for making the box-forming assemblies, nor do I lay claim herein to the instrumentalities for forming the assemblies in box form, as such mechanism and instrumentalities are claimed in my co-pending 30 application filed, September 16, 1921, Serial No. 501,088, although one form of mechanism for carrying out my new method is already claimed in its broader aspect in my co-pending application, Serial No. 254,630, 35 filed September 18, 1918.

What I claim is:

1. The method of making covered paper boxes, which consists in assembling in superposed relation, a substantially flat box-shell 40 blank having a body portion and side and end wings, and a wrapper blank of greater dimensions than the shell blank, to provide free marginal portions at the sides and ends thereof, infolding said side marginal portions 45 over opposite edges of the side wings of the shell blank while the latter is maintained substantially flat to provide an "assembly", then folding the assembly into box form, and finally inturning the remaining marginal portions of the cover blank 50 over the edges of their associated end walls and adhesively attaching the same to the inner faces of such walls, to provide a permanently "set-up" and covered box shell.

55 2. The method of making covered paper boxes, which consists in applying adhesive to a face of a substantially flat box-shell blank of relatively stiff material which has a body portion and side and end wings, 60 locating the shell blank flatwise upon a flat wrapper blank of greater dimensions than the shell blank to provide free marginal portions, infolding side marginal portions of the wrapper blank over opposite edges of 65 the side wings of the shell blank and af-

fixing them thereto while they are supported substantially flat, then folding the assembly thus formed into box-shell form, and finally inturning the remaining marginal portions of the wrapper blank over the edges of their 70 associated box walls and adhesively attaching the same to the inner faces of such walls, to provide a permanently "set-up" structure.

3. The method of making covered paper boxes, which consists in assembling in superposed relation, a substantially flat box-shell blank having a body portion and side and end wings, and a wrapper blank of greater dimensions than the shell blank, infolding marginal portions of the wrapper blank over 75 and adhesively affixing them to opposite adhesively coated marginal edges of the uncovered face of the shell blank to provide a substantially flat "assembly", then folding the assembly into box form, and finally inturning the marginal portions of the cover blank at the ends of the box over the edges of and adhesively attaching them to the inner faces of the end walls of the box, to provide a permanently "set-up" structure. 80

4. The method of making covered paper boxes which consists in applying zones of adhesive to a face of a box shell-blank having a body portion and side and end wings, advancing the freshly coated shell blank and 85 arranging it in superposed relation with a wrapper blank of greater dimensions than the shell blank to provide free marginal portions, inturning the said free marginal portions over and adhesively affixing them to 90 the adhesively coated zones of the shell blank to provide a substantially flat "assembly", and then folding the assembly into box form.

5. In a method of making covered paper 105 boxes, the steps which consist in assembling while in a substantially flat condition, an adhesively stenciled shell-blank and a wrapper blank, and in inturning marginal portions of the wrapper blank over and affixing 110 them to adhesively stenciled portions of the shell blank, while the latter is in a substantially flat condition, to provide a substantially flat box-forming "assembly".

6. The herein described method of making covered paper boxes, which consists in applying adhesive to a substantially flat box-shell blank having a body portion and side and end wings, then applying a wrapper blank of greater dimensions than the shell 120 blank to the adhesively coated face of the flat shell blank, and then folding marginal edges of the said wrapper blank over and affixing them to adhesively coated portions of the shell blank while the latter is maintained in a substantially flat condition, to provide a box forming "assembly".

7. The method herein described of making covered paper boxes, which consists in applying adhesive to opposite faces of a 125

substantially flat box-shell blank having a body portion and side and end wings, then combining said shell blank with a wrapper blank having side and end wings of greater dimensions than the shell blank, to provide a substantially flat adhesively connected "assembly", then inturning opposite marginal portions of the wrapper blank wings over the opposite edges of and pressing them upon the adhesively coated portions of the shell blank wings while said wings are maintained substantially flat, then folding the assembly into box form, and finally inturning the remaining marginal portions of the wrapper blank over the opposite edges of and pressing them against the adhesively coated inner faces of their associated box-shell wings.

8. The method herein described of making covered paper boxes, which consists in applying adhesive to opposite faces of a substantially flat shell-blank having a body portion and side and end wings, the adhesive on one face being applied in stripes or zones adjacent the marginal edges of the wings, then combining said shell blank with a wrapper blank of greater dimensions than the shell blank to provide a substantially flat adhesively connected "assembly", then inturning opposite marginal portions of the wrapper blank wings over the opposite edges of and pressing them upon the adhesively coated marginal portions of the shell blank wings while said wings are substantially flat, to provide a flat box-forming "assembly".

9. The herein described method of producing a flat assembly from which covered paper boxes may be made, which consists in advancing a box-shell blank having a body portion and side and end wings, applying adhesive to one face of said blank while it is being advanced, and then superposing the shell blank flatwise onto a face of a flat uncoated wrapper blank of greater dimensions than the shell-blank, to provide an "assembly".

10. The herein described method of producing a flat embryo box forming assembly, which consists in applying adhesive to opposite faces of a substantially flat box-shell blank having a body portion and side and end wings, the adhesive being applied in zones or stripes on one of said faces, then advancing the coated blank and bringing a face thereof in superposed relation with a face of an uncoated wrapper-blank of greater dimensions than the shell-blank, to provide a connected "assembly", and then inturning opposite marginal portions of the wrapper blank over opposite marginal edges of the shell blank and pressing them upon the said adhesively coated zones or stripes of the shell blank.

11. The herein described method of producing a substantially flat assembly from

which covered paper boxes may be formed, which consists in advancing a substantially flat box-shell blank having a body portion and side and end wings, applying adhesive to a face of said blank, advancing the blank to bring it opposite a pack of uncoated wrapper blanks each having a body portion and side and end wings of greater dimensions than the shell blank, then bringing the shell blank and the uppermost wrapper blank of the pack into facial contact to cause them to become adhesively connected, and then advancing the "assembly".

12. In a method of making covered paper boxes, the steps which consist in stenciling a substantially flat box shell blank, then superposing the stenciled blank onto a substantially flat cover blank, and then inturning the marginal edges of the cover blank over and adhesively affixing such edges to stenciled portions of the shell blank to provide a substantially flat box-forming assembly.

13. In a method of making covered paper boxes, the steps which consist in stenciling a substantially flat box shell blank, then superposing the stenciled blank onto a substantially flat cover blank, then inturning the marginal edges of the cover blank over and adhesively affixing such edges to stenciled portions of the shell blank to provide a box-forming assembly, and then folding the said assembly into box form and affixing the remaining marginal edges of the cover blank to the inner walls of the formed box.

14. In a method of making covered paper boxes, the steps which consist in stenciling a substantially flat box shell blank on one face and applying adhesive throughout substantially the entire area of its other face, then superposing the adhesively coated face of the shell blank onto a substantially flat cover blank, then turning the marginal edges of the cover blank over and adhesively affixing such edges to stenciled portions of the shell blank to provide a box forming assembly.

15. In a method of making covered paper boxes, the steps which consist in stenciling a substantially flat box shell blank on one face and applying adhesive throughout substantially the entire area of its other face, then superposing the adhesively coated face of the shell blank onto a substantially flat cover blank, then turning the marginal edges of the cover blank over and adhesively affixing such edges to stenciled portions of the shell blank to provide a box-forming assembly, and then folding the said assembly into box form and affixing the remaining marginal edges of the cover blank.

16. In a method of making covered paper boxes from a shell blank having a body portion and side and end wings, and a cover blank of greater dimensions than the shell

- blank, the steps which consist in applying adhesive to a face of the shell blank, then depositing the said blank flatwise onto a flatwise supported cover blank leaving free
- 5 marginal portions of the cover blank projecting beyond the marginal edges of the side and end wings of the shell blank, and then in turning the two opposite side marginal portions of the cover blank over and adhesively
- 10 affixing them to the opposite face of the shell blank to cover the edges thereof and provide an assembly which may be folded into a box.
17. The method of making covered paper boxes from an assembly consisting of a box
- 15 shell blank having a body portion and side and end wings, and a cover blank of greater dimensions than the shell blank, which consists in applying adhesive to a face of the shell blank, then combining the said shell
- 20 blank with the cover blank and adhesively connecting them to provide a substantially flat assembly, and then folding the assembly into "set-up" box form with marginal portions of the cover blank overlying the edges
- 25 of and adhesively attached to the inner faces of the box walls.
18. In a method of forming covered box shells from an assembly including a box shell blank and a cover blank and wherein
- 30 said blanks have integral side wings with foldable corner laps and also have end wings, the step which consists in inturning the corner laps at the ends of the box and simultaneously infolding portions of the cover
- 35 blank adjacent the corners of the box to cause them to lie in between the adjacent faces of the shell blank end wings and their companion corner laps to cover the opposite raw edges of said end wings.
- 40 19. In a method of making covered paper boxes, the steps which consist in assembling while in a substantially flat condition, an adhesively coated shell-blank having side and end wings defined by scored or creased
- 45 folding lines, and a wrapper blank of greater dimensions than the shell blank, to provide a box-forming assembly, and then bending the assembly along the scored or creased lines.
20. In a method of making covered paper boxes from an assembly consisting of a shell-blank having side and end wings with corner-laps at the opposite ends of the side wings, and an attached wrapper blank of greater dimensions than the shell blank, the
- 50 steps which consist in folding the covered side wings of the assembly at right angles to the body thereof, then folding the corner-laps inward toward each other at the ends of the box and the end wings up parallel with
- 55 said corner-laps and infolding portions of the wrapper-blank adjacent the box corners to cause them to lie in between the adjacent faces of the corner laps and their associated end wings and cover the raw side edges of
- 60 said wings.
21. In a method of forming covered paper boxes from an assembly consisting of a shell-blank having a body portion and side and end wings with corner-laps at the opposite
- 65 ends of the side wings, and an attached wrapper blank of greater dimensions than the shell-blank, the steps which consist in folding the side wings of the assembly at right angles to the body portion, then folding the corner-laps inward toward each other at the ends of the box and the end wings up parallel therewith, forming gusset
- 70 or bellows folds in the free portions of the wrapper blank adjacent the box corners and
- 75 infolding such gusset or bellows folds to cause them to lie flat between the adjacent faces of the corner-laps and their associated end wings and cover the raw side edges of
- 80 said wings.
- 85 Signed at New York in the county of New York and State of New York this 29th day of March A. D. 1920.

HARRY BRIDGMAN SMITH.
